UNITED STATES PATENT OFFICE.

FRANK C. ROBERTS, OF PHILADELPHIA, PENNSYLVANIA.

REGENERATIVE HOT-BLAST STOVE.

No. 856,300.

Specification of Letters Patent.

Patented June 11, 1907.

Application filed February 25, 1907. Serial No. 359,321.

To all whom it may concern:

Be it known that I, FRANK C. ROBERTS, a citizen of the United States, residing at Philadelphia, in the county of Philadelphia and 5 State of Pennsylvania, have invented certain new and useful Improvements in Regenerative Hot-Blast Stoves, of which the following is a specification, reference being had to the accompanying drawings.

10 In said drawings, Figure 1 represents a vertical section through the stove on the line X X of Fig. 4. Fig. 2 is a central vertical section through the stove on the line Y Y of Fig. 4. Fig. 3 is an irregular horizontal section upon two different planes indicated by the line Z Z' in Fig. 1. Fig. 4 is a horizontal section on line U U of Fig. 2. Figs. 5, 6, 7, 8, 15 9, 10, 11 and 12 represent horizontal sections through stoves wherein the number and arrangement of walls and compartments is varied as hereinafter explained.

The stove is cylindrical in form and its chief characteristics are that it has a central combustion chamber with regenerators located around the combustion chamber, said 20 regenerators being so arranged and connected that when gas is burned in the combustion chamber, the products of combustion on leaving the combustion chamber pass downward through certain of said regenerators and thence upward through the remaining chambers to the upper part of the stove and thence to the chimney located at the top of the stove.

Referring to the drawings, A represents 25 the exterior metal shell of the stove and B the exterior metal shell of the chimney.

C is the combustion chamber formed by the circular wall D within the inclosing walls E.

30 F are sections of chord walls extending horizontally from the outside wall G to the walls E and vertically from the bottom to near the top of the stove. These walls F divide the space between the walls G and E 35 into eight compartments. By reference to Fig. 4 it will be seen that four of these compartments marked H are rectangular in horizontal section while the remaining four compartments I are approximately of quadrant 40 shape in horizontal section. The walls F terminate near the top of the stove in two arches J, located at right angles to each other, extending entirely across the diameter of the stove between the walls G, the intersection 45

of the arches being central with the center of 55 the stove, the whole so constructed that free access and communication is provided between the top of the combustion chamber C and the tops of the four rectangular compartments H and that access and communication 60 between the top of C and the tops of the quadrant shaped compartments I is prevented. As indicated, the walls F are supported on the stove bottom; at or near the bottom of walls F, openings K are provided 65 whereby access and communication is furnished between the bottoms of compartments H and the bottoms of compartments I. Near the top of the stove, compartments I communicate with the space L which space in 70 turn communicates with the chimney M.

Compartments H and I form the regenerator chambers and the filling forming the regenerators may be constructed in any approved manner and in accord with any suitable design, and is therefore not described in detail. Said regenerators may be supported in any approved manner. In the drawings the regenerators in compartments H are shown as supported by lintels N and piers O 80 while the regenerators in compartments I are supported by lintels N and arches P. Piers O may be provided with arched openings R. The regenerators in compartments H terminate at or near the top of the combustion chamber C in such a manner as to leave free communications between C and the regenerators in H. The regenerators in compartments I terminate at or near the top 85 of the arches J; free communication between the regenerators in I and the space L 90 being provided.

At the bottom of the stove four arched openings (a) are provided leading from the outer walls G to the combustion chamber C; as 95 shown on the drawings these openings are formed by arches (b) extending between walls F and under compartments H, the walls F being thickened to carry the arches. It is to be noted that the arched openings (a) 100 are so constructed as to communicate only with C and in no case with H or I. The gas inlet S and the hot blast outlet T communicate with C through openings (a) as indicated while air doors or cleaning doors (e) likewise 105 communicate with C in a similar manner. The sloping walls V are provided under H and I to facilitate the removal of dirt from H

by delivering the dirt under I from whence it may be removed through doors (f). Cleaning doors (f) are also provided at the top of the stove for cleaning purposes. The chimney M is provided with a valve (g); the cold air blast enters the stove by means of air pipe (h) equipped with valve (h'); all as indicated.

The method of operation is as follows:—
10 The air inlet valve (h') and the hot blast outlet T being closed and the chimney valve (g) and the valve of gas inlet S being open, the combustible gas passes into C where it comes in contact with air admitted through one or more of the arched openings (a) and is ignited. From C the products of combustion pass downward through the regenerators in compartments H and thence upward through the regenerators in compartments I into L
15 and from thence escape to the atmosphere through chimney M. This direction of the currents while the stove is "on gas" is of course reversed when the stove is "on blast." In the latter event, the chimney valve (g) and the valve of the gas inlet S being closed and the air inlet valve (h') and the hot blast outlet T being opened, the air enters L and passes downward through the regenerators in compartments I, thence upward through the regenerators in compartments H and thence downward through C to one of the arched openings (a) whence it finds its exit through the hot blast outlet T. If desired, partial or complete combustion may be effected in the arched opening (a) to which the gas inlet is connected by means of air openings leading into said arched opening (a).

Among the advantages arising from the above described construction are the following:—The central combustion chamber concentrates the heat of combustion in the center of the stove, the radiation therefrom being outward into the regenerators. Again it is evident that all regenerators being in contact with the outer walls G, said regenerators are readily accessible for cleaning through openings in A and G above and under the regenerators. Further the cleaning of the regenerators is facilitated by the ready communication which exists between the spaces under the regenerators and the ease with which dirt in the regenerators in compartments H may be removed from the stove by means of the cleaning doors communicating with the space under the regenerators in compartments I.

It is evident that it is possible to vary the number and arrangement of walls F which divide the space between walls G and E into compartments for use as regenerators. I have indicated several possible variations in Figs. 5, 6, 7, 8, 9, 10, 11 and 12. Figs. 5, 7, 9 and 11 are sections on lines corresponding to line W Z' of Fig. 1. Figs. 6, 8, 10 and 12 are

sections on lines corresponding to line U U of Fig. 2. Figs. 5 and 6 show walls whereby two regenerator compartments are provided. Figs. 7, 8, 9 and 10 show walls whereby four regenerator compartments are provided and Figs. 11 and 12 show walls whereby six regenerator compartments are provided. In all of these instances, as in Figs. 1, 2, 3 and 4, the products of combustion pass from the top of the central combustion chamber C into and downward through the regenerators H thence through openings K and upward through regenerators I from whence they pass to the chimney.

For the sake of clearness I desire to denote the regenerators in compartments H through which the products of combustion pass downward as "down-pass" regenerators and the regenerators in compartments I through which the products of combustion pass upward as "up-pass" regenerators.

I do not limit the combustion chamber in horizontal section to the circular shape shown on the drawings; it may be rectangular in cross section or any other suitable shape.

Having fully described my invention, what I claim, and desire to cover by Letters Patent, is—

1. In a hot blast stove, the combination of an outside wall, a central combustion chamber surrounded by a wall, four down-pass regenerators communicating with the top of said combustion chamber, four up-pass regenerators communicating with the bottom of said down-pass regenerators, a chimney arranged above and communicating with said up-pass regenerators, said eight regenerators being placed in compartments surrounding the combustion chamber and extending to said outside wall and formed by walls extending from said outside wall to said wall surrounding the combustion chamber.

2. In a hot blast stove, the combination of an outside wall, a central combustion chamber surrounded by a wall, one or more down-pass regenerators communicating with the top of said combustion chamber, one or more up-pass regenerators communicating with the bottom of said down-pass regenerators, a chimney arranged above and communicating with said up-pass regenerators, said down-pass and up-pass regenerators being placed in compartments surrounding said combustion chamber and extending to said outside wall and formed by walls extending from said outside wall to said wall surrounding the combustion chamber.

3. In a hot blast stove, the combination of an outside wall, a central combustion chamber surrounded by a wall, a series of two or more regenerators surrounding said combustion chamber and extending to said outside

wall and located in compartments formed by walls extending from said outside walls to said wall surrounding the combustion chamber, means of communication between the top of the combustion chamber and the down-pass regenerators, means of communication between the bottoms of the down-

pass regenerators and the up-pass regenerators and a chimney arranged above and communicating with said up-pass regenerators. 10
